G. A. LUND.

PADLOCK.

APPLICATION FILED OCT. 27, 1919.

1,349,682.

Patented Aug. 17, 1920.

INVENTOR:

Gustav A. Lund
BY his ATTORNEY:
A. M. Carlsen.

UNITED STATES PATENT OFFICE.

GUSTAV A. LUND, OF STILLWATER, MINNESOTA.

PADLOCK.

1,349,682.

Specification of Letters Patent. Patented Aug. 17, 1920.

Application filed October 27, 1919. Serial No. 333,839.

To all whom it may concern:

Be it known that I, GUSTAV A. LUND, a subject of the King of Norway, who have declared my intention to become a citizen 5 of the United States, residing at Stillwater, in the county of Washington and State of Minnesota, have invented a new and useful Padlock, of which the following is a specification.

10 My invention relates to pad-locks, and the object is to provide a novel simple yet efficient pad-lock.

In the accompanying drawing, Figure 1 is an end view of the improved lock looking toward the key-hole of it. Fig. 2 is a section on the line 2—2 in Fig. 1. Fig. 3 is a cross section of the lock as on the line 3—3 in Fig. 2. Fig. 4 is a cross section as on the line 4—4 in Fig. 2. Fig. 5 is a side view of the key only. Fig. 6 is a section as on the line 6—6 in Fig. 2 showing a slight modification.

Referring to the drawing by reference numerals, 7 is the hollow shell or body of the lock and may be of cylindrical form; it is provided with two lugs 8, in which is pivoted at 9 a shackle 10, whose end 11 extends through an aperture 12 in the shell and is provided with a recess 13 adapted to be engaged by the reduced end portion 14 of a screw 15 which has very coarse threads in a partition 16 of the shell. The other end of the screw is formed with a stem 17, which in my drawing is shown to be four-cornered, but it may in some cases be triangular, hexagon or of any other polygonal form in the various locks. To prevent accidental or too easy rotation of the screw, a spring 18 is fixed in the shell and arranged 40 to press against one side of the round stem 14 (see Fig. 4). After said screw and spring are inserted, the open end of the shell is closed by a bottom 19, fitted into a recess 20 in the shell and beveled at its outward edge whereupon the edge 21 of the shell is closed inward upon the beveled portion of the bottom, so that the bottom and the shell look as if they were cast in one piece.

50 The other end of the shell is provided with a slit-like key hole 22 which may be slightly enlarged in the middle, as at 23 in Fig. 1 for the bar 24 of a key 25, whose outer end 26 may be of any suitable form.

55 The inward end of the key is flattened and

formed into an arch 27, whose end portion 28 is provided with an aperture 28* adapted to fit upon the stem 17 of the screw and turn it.

To prevent picking of the lock by false keys, the lock shell is provided near the key hole with two internal segmental obstructing lugs 29 and 30, and two longitudinal lugs or embossments 31 and 32. The latter has its inner end reduced to a radial rib 33, having an arm 34 extended to the center of the shell and there terminating in a disk 35 which serves as a guard against false keys. Said guard is spaced sufficiently away from the stem 17 to admit the portion 28 of the key to enter between said parts even when the screw is in the retracted position for releasing the shackle.

In the operation or use of the lock, the key is inserted by hooking it into the shell over the guard 30, as shown in dotted lines 26^a in Fig. 2; it is then brought to axial position, and thence to the position 26^b, so its part 28 will pass the guard 35. The key is then brought to the axial position 26^c and pushed upon the stem 17. Next the key is turned from the position 24 to the position 24* in Figs. 3 and 6, which turning is fully three-fourths of a full rotation and is sufficient to disengage the screw from the shackle 10, 11, and thus open the lock. In closing the lock, the key is likewise inserted and turned in the opposite direction until it stops at the other side of the arm 34 whereupon it is removed from the lock.

Any suitable form of spring may be used for throwing the shackle open when unlocked, but as such springs are not my invention I have not shown or described the same.

What I claim is:—

1. A padlock comprising an elongated hollow body with a slit-shaped key-hole in one end and an aperture in one side near the other end of the body, a shackle pivoted to the shell and having its free end provided with a recess and arranged to swing into the aperture, said shell having near the aperture a partition, a screw threaded in the partition and provided at one end with a round stem adapted to enter the recess in the shackle, the other end being polygonal and adapted to be engaged by a key fitting the polygonal form of the stem, a radial arm fixed in the shell and having at its 105

end a disk spaced a short distance from and coaxially with the polygonal stem so as to guard the latter, a key adapted to be inserted into the lock through the key-hole and having a laterally arched end portion, the front leg of the arch being flat and extended across the axis of the bar of the key, and at said axial point provided with an

aperture adapted to fit the polygonal end of the screw.

2. The structure specified in claim 1, and a friction spring arranged to press against one side of the screw to prevent accidental rotation of the latter.

In testimony whereof I affix my signature.

GUSTAV A. LUND.
